UNITED STATES PATENT OFFICE.

EIMER G. GAETIN, OF CLAREMONT, NEW HAMPSHIRE, ASSIGNOR TO SULLIVAN MACHINERY COMPANY, A CORPORATION OF MASSACHUSETTS.

FEEDING MECHANISM.

Application filed December 23, 1920. Serial No. 432,781.

My invention relates to feeding mechanisms and more especially to feeding mechanisms for use in connection with rock drilling machinery.

- 5 An object of my invention is to provide an improved feeding mechanism. Another object of my invention is to provide an improved feeding mechanism of the fluid pressure type. A further object of my invention is to provide an improved feeding mechanism of the liquid pressure type comprising means for producing by means of a compact mechanism a liquid pressure and applying it to the production of movement of my feeding device. 10 15 20 25 30 35 40 45 50 55 60 65 70 75 80 85 90 95 100 105 110
- 5 A still further object of my invention is to provide an improved rotating and drill feeding mechanism. Other objects of my invention will appear in the course of the following specification.
- 20 In the accompanying drawings I have shown for purposes of illustration one embodiment which my invention may assume in practice.

In these drawings,—

- 25 Fig. 1 is a central longitudinal section through the feed cylinder and the rear end of the percussive cylinder of a stoping drill provided with my improved mechanism.

Fig. 2 is a central section, on a plane at right angles to the plane of Fig. 1, through the cylinder of a percussive motor embodying my improved rotating and feeding mechanism.

Fig. 3 is a transverse section on the line 3—3 of Fig. 1.

- 35 Fig. 4 is a similar section on the line 4—4 of Fig. 1.

Fig. 5 is a diagrammatic view showing the circulation of the liquid under pressure to and through my improved feeding mechanism.

- 40 In the illustrative embodiment of my invention I have shown the same used in connection with a stoping drill generally indicated by the numeral 1 and comprising a fluid pressure percussive motor 2, a feeding mechanism proper 3, an auxiliary motor 4 designed to effect rotation of the drill steel and to produce power for the production of a liquid pressure, and a liquid pressure generator 5 driven by the motor 4.

50 The percussive motor 2 is of a well-known type and comprises a cylinder 6 in which is reciprocable a piston 7 under the action of live fluid distributed in a well-known manner to the opposite ends of the cylinder 6, said piston 55 60 65 70 75 80 85 90 95 100 105 110

ed to cooperate with the rear end of a drill steel 9 carried in a chuck 10 rotatably mounted in the front end of a cylinder head 11, which latter is secured to the cylinder member 6 by means of side rods 12. Rigidly secured within the casing of the pump 5 and projecting laterally from the machine is a usual supporting handle 5^a adapted to be grasped by the operator to support the machine and to prevent bodily rotation of the machine about the axis of the drill steel. For the purpose of rotating the chuck member 10, and accordingly the drill steel 9, I have provided at the rear end of the cylinder 6 a rotary motor generally designated 4 and comprising a series of three rotors designated respectively 13, 14, and 15, these rotors being mounted in a suitable housing 16 in which are formed intersecting chambers 17, 18 and 19 in which the rotors 13, 14 and 15 are respectively housed, it being understood that the rotors are provided about their peripheries with intermeshing teeth 20 and that fluid pressure is supplied adjacent the mesh line of said teeth in such manner as to cause rotation of said rotors. The rotor 14 is located between the rotors 13 and 15, and fluid pressure is admitted at diametrically opposite points by means of passages 21 and 22 to points adjacent the mesh line between the rotors 13, 14, and 14 and 15. Fluid is conducted away from the opposite sides of the mesh lines of these rotors by passages 23 and 24. Fluid supply to the passages 21 and 22 is controlled by the valve mechanism generally indicated by 25 which likewise controls a supply of fluid pressure to the percussive motor 2. The several rotors are mounted in a suitable manner, the central rotor 14 being mounted on a stub shaft arranged coaxially with the piston 7 and journaled in opposite sides of the housing 16 and extending through a pump chamber 26 and carrying in said pump chamber one rotor 27 of an intermeshing pair of rotors constituting an oil pump, the other of these rotors being designated 28 and mounted in meshing relation with rotor 27. The rotor 15 is journaled on one of the side rods 12, as is also the rotor 28, and the rotor 13 is journaled on the other side rod and provided upon its forward end with a sleeve member 29 extending forward in parallelism with the drill cylinder through a passageway 30 and clutched at its forward end as at 31 to a similar tubular sleeve 32, which carries at 110

its forward end a spur gear 33 meshing with the spur gear 34 formed on the periphery of the chuck member 10. It will thus be obvious that as fluid pressure is supplied to the rotors 5 of the motor 4 the motor will simultaneously supply power for the rotation of the drill steel, which power is transmitted thereto by way of the tubular shafts 29 and 32 and the intermeshing spur gears 33 and 34 (although 10 it will be clear that further gear reduction may be used) and also will drive the oil pump 5 and thereby produce a suitable source of liquid pressure for feeding the drill steel to the work. It will be understood that the teeth 15 on the rotors 27 and 28 constituting the oil pump are narrower and of less height than the teeth on the rotors of the motor 4 whereby a surplus of power is provided by the fluid pressure motor 4 for use in rotating the drill 20 steel.

The oil pumping system operated by the pump 5 comprises a storage chamber 35 communicating with a suitable oil supply 36 closed normally by a plug 37 and adapted to 25 supply oil by way of a passage 38 to a point adjacent the mesh line of the rotors 27 and 28 and oil is pumped by said rotors by way of a passage 39 to the ends of the feeding mechanism. To prevent building up of an 30 excessive pressure and stalling of the pump, a spring loaded by-pass 40 connects the discharge line 39 with the suction line 38. At a point beyond the by-pass 40 the discharge line 39 opens into a valve casing 41 from 35 whose sides, at points separated by 90° from the port 39, there extend passages 42 and 43 to the rear and front ends of a feed cylinder 44 respectively. It will be understood that as oil is supplied to the front end of the cylinder 44 it will act upon a piston 45 disposed 40 therein and force the cylinder in a forward direction and that oil supplied through the line 43 to the rear end of the cylinder will cause movement of the cylinder in an opposite direction with respect to the piston. It 45 will be understood that suitable means are provided for conducting oil from one end of the cylinder while it is being supplied to the other and this is accomplished by arranging 50 a discharge port 46 at a point diametrically opposite the port 39 and the formation, in a valve 47 located in the valve chamber 41, of oppositely disposed passages 48 and 49. These passages so cooperate with the ports 55 42 and 43 that while the port 39 is connected for example by way of passage 48 to the passage 43 for the supply of liquid pressure to the front end of the feed cylinder, the passage 42 leading from the rear end of the 60 feed cylinder is connected by way of the groove 49 to the discharge passage 46 and hence by way of the chamber 35 to the suction side of the pump. It will be understood that the maximum pressure obtainable by this 65 pumping means may readily be adjusted by

varying the tension of a spring 50 controlling the check valve 51 in the by-pass 40 by any suitable means not shown. It will also be understood that during normal forward feed the oil is supplied to the front end of the 70 cylinder at such a rate as to maintain the steel, when the percussive motor is idle, a distance from the rock slightly greater than the penetration when the steel is hammered. It will be further understood that by limiting the rate at which liquid is supplied to either end of the cylinder, it will be possible to control the rate of movement of the piston and that when moving the steel up to the work or retracting it a rapid feed is possible. 80 It is also obvious that as the resistance encountered by the drill steel varies the speed of the motor 4 and consequently the speed of the pump 5 varies, thus causing a resultant variation in the feeding pressure. 85

While I have in this application specifically described one form which my invention may assume in practice, it will be understood that this form of the same is shown for purposes of illustration and that the invention 90 may be modified and embodied in other forms without departing from its spirit or the scope of the appended claims.

What I claim as new and desire to secure by Letters Patent is:

1. A drilling mechanism comprising a drilling motor, a drill steel receiving chuck carried thereby, a motor carried by and movable with said drilling motor during feeding for rotating said chuck relative to said drilling motor, and feeding means constituting a support for said motor and including means operated by said rotation motor to effect feeding. 100

2. A drilling mechanism comprising a drilling motor for actuating a drill steel, a motor for rotating the steel about its axis, fluid actuated feeding means for the steel disposed in axial alignment therewith, and pressure generating means operatively connected to said rotation motor for placing under pressure the fluid in said feeding means, said generating means being responsive to load changes on said rotation motor. 110

3. In a drilling mechanism, a drilling motor of the hammer type, a motor for rotating a drill steel about its axis, and fluid actuated feeding means for the steel constituting a support for said motor and including a pressure generating pump, said pump being driven by said rotation motor and responsive to the load changes on the latter. 115

4. In a rock drilling mechanism, a tool receiving chuck, rotatable means for transmitting rotation to said chuck, rotatable means for feeding said chuck, a multi-rotor motor, and shafts driven by different rotors of said motor driving said first and second mentioned means. 125

5. In a rock drilling mechanism, a drilling 130

- motor comprising a cylinder member having front and back heads, side rods for securing said heads to said cylinder, a tool rotation motor carried within said back head, and 5 feeding means including a pump, said second mentioned motor and said pump each having component elements rotatable on said side rods.
6. A drilling mechanism comprising a 10 drilling motor having a tool receiving chuck, fluid pressure operated means for feeding said chuck and motor simultaneously, a head carried by said motor, and means including a motor disposed within said head for rotating said chuck and actuating said feeding mechanism.
7. A drilling mechanism comprising a 15 drilling motor having a tool receiving chuck, fluid operated means for feeding said chuck and motor simultaneously, a head carried by said motor, means including a motor disposed within said head for rotating said chuck and actuating said feeding mechanism, said head having a fluid chamber, and means 20 whereby fluid therein can have communication with said means carried by said head during feeding.
8. In a drilling mechanism, a drill steel, 25 means for rotating the steel, cylinder and piston elements adapted to be relatively moved by pressure fluid to feed said steel, and means operative when the drilling mechanism is held against rotation for automatically controlling the pressure in said cylinder element in accordance with the resistance 30 to drill steel rotation.
9. In a drilling mechanism, a drill steel, 35 means for rotating the steel, pressure fluid actuated feeding means for the steel, and means operative when the drilling mechanism is held against rotation for automatically controlling the pressure in said feeding means in accordance with the resistance to drill steel rotation.
- 40 10. In a drilling mechanism, the combination of a drill steel, means for rotating the drill steel, pressure fluid actuated feeding means for the steel, means having fixed relation with the mechanism adapted to prevent 45 rotation of the latter about the axis of the steel, and means responsive to the load changes on said rotation means for automatically controlling the pressure in said feeding means.
- 55 11. In a drilling mechanism, the combination of a rotary drill steel rotating motor, 50 pressure fluid actuated feeding means for the steel, and means responsive to the torque of said rotary motor when the drilling mechanism is held against rotation for automatically controlling the pressure in said feeding means.
- 60 12. In a drilling mechanism, a drilling motor, a drill steel actuated thereby, means for 65 rotating the drill steel, pressure fluid actu- ated feeding means for the steel, means having rigid fixed relation with said motor adapted to prevent rotation of the latter about the axis of the steel, and means whereby resistance to drill steel rotation automatically varies the operation of both said rotation and feeding means including means for controlling the pressure transmitted by said feeding means in accordance with the requirements of the work.
- 70 13. In a drilling mechanism, a drilling motor having a drill steel receiving chuck, a motor for rotating the chuck, fluid actuated feeding means for the steel, means having rigid fixed relation with said motor adapted to prevent rotation of the latter about the axis of the steel, and means whereby said feeding means is controlled automatically in accordance with resistance to drill steel rotation operative to control the pressure transmitted by said feeding means in accordance with the requirements of the work.
- 75 14. In a drilling mechanism, the combination of a drill steel, means for rotating the drill steel, means for feeding the steel, means having rigid fixed relation with the mechanism adapted to prevent rotation of the latter, and means whereby said feeding means is controlled automatically in accordance with resistance to drill steel rotation operative to control the pressure transmitted by said feeding means in accordance with the requirements of the work.
- 80 15. In a drilling mechanism, a drilling motor of the hammer type, drill steel rotation means, means for feeding the steel, and means whereby said feeding means is automatically controlled in accordance with the resistance to drill steel rotation including a plurality of dependently operable pressure fluid actuated means and operative to control the pressure transmitted by said feeding means in accordance with the requirements of the work.
- 85 16. A drilling mechanism comprising a cylinder, heads therefor, a tool receiving chuck carried by the front head, side rods for connecting said heads and cylinder, and means associated with the rear head for rotating said chuck including an independent rotary motor having a rotary motor element associated with one of said side rods.
- 90 17. A drilling mechanism comprising a motor having a plurality of parts, side rods for connecting the same, a tool receiving chuck, means for rotating said chuck including an independent plural-rotor motor having a motor element disposed on one of said side rods, and a second element cooperating therewith and disposed coaxially with said drilling motor at the rear end thereof.
- 95 18. In a rock drill, a drilling motor comprising a cylinder, front and rear heads therefor, and a piston reciprocable in said cylinder, a casing at the rear end of said
- 100 105 110 115 120 125 130

- cylinder and having intersecting rotor chambers and secured to said rear head, a rear head member closing the bores of said casing, a drill steel rotation motor comprising intermeshing toothed rotors disposed in the bores in said casing, said motor having a large central rotor disposed coaxially with said piston and cooperating smaller rotors disposed on parallel axes at opposite sides thereof, a drill steel receiving chuck rotatably mounted in said front head, and transmission means including means connecting one of said smaller rotors and said chuck for transmitting rotary motion to the latter and said steel. 55
- 15 19. In a rock drill, a drilling motor comprising a cylinder, front and rear heads, and a piston reciprocable in said cylinder, a motor casing at the rear end of said cylinder and secured to said rear head and having parallel 60 intersecting bores, a drill steel rotation motor comprising a large central rotor disposed in one of said bores coaxially with said piston, and cooperating smaller rotors disposed on parallel axes at opposite sides of said central 65 rotor in said other bores, a drill steel receiving chuck rotatably mounted in said front head, and transmission means including means connecting one of said smaller rotors and said chuck for transmitting rotary motion to the latter and the steel. 70
